CLAIM

I claim the ornamental design for a bag dispenser rack, as shown and described.

DESCRIPTION

FIG. 1 is a front perspective view of my new bag dispenser rack. The dash lines showing the bag dispenser in the racks are for illustrative purposes only, and are not intended to form a portion of the claimed design. The dash line representation of holes in the bottom and end mounting plates is also for illustrative purposes only, and is not intended to form a portion of the claimed design.

FIG. 2 is a front perspective view of the bag dispenser rack.

FIG. 3 is a front side elevational view thereof.

FIG. 4 is a top plan view thereof.

FIG. 5 is a bottom plan view thereof.

FIG. 6 is an end elevational view taken from the right end in FIG. 2; and,

FIG. 7 is an end elevational view taken from the left end in FIG. 2.
